CLAIM

The ornamental design for a wall plate, as shown and described.

DESCRIPTION

FIG. 1 is a front perspective view of an embodiment of the wall plate;

FIG. 2 is a front view of the wall plate of FIG. 1;

FIG. 3 is a right side view of the wall plate of FIG. 1;

FIG. 4 is a left side view of the wall plate of FIG. 1;

FIG. 5 is a top view of the wall plate of FIG. 1;

FIG. 6 is a bottom view of the wall plate of FIG. 1; and,

FIG. 7 is a back view of the wall plate of FIG. 1.
